UNITED STATES PATENT OFFICE.

HERMAN L. WAGNER, OF MOUNT VERNON, NEW YORK, ASSIGNOR TO UNDERWOOD TYPEWRITER COMPANY, OF NEW YORK, N. Y., A CORPORATION OF NEW JERSEY.

TYPE-WRITING MACHINE.

No. 848,788.

Specification of Letters Patent.

Patented April 2, 1907.

Application filed May 7, 1906. Serial No. 315,608.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates to the mechanism of type-writing machines which vibrates the ribbon to cover and uncover the printing-point at the type-strokes. Usually the ribbon is threaded through a carrier, and the latter is connected to a lever which is vibrated at each type-stroke, this movement being effected by means of an actuator, which is mounted upon the usual universal-bar frame and connected to said lever.

The principal object of my invention is to provide inexpensive and convenient means for silencing the ribbon-carrier at will, so that it shall not operate during the type-strokes, whereby the types may print off the ribbon for stenciling and other work. For this purpose I mount a wrist upon said lever in such a manner that the wrist may be moved in axial direction to disconnect it from said actuator, and I connect to this wrist a finger-piece, whereby the operator may conveniently unship the wrist, this finger-piece so connected that it does not interfere with the vibrations of the lever when connected to the actuator.

In the accompanying drawings, Figure 1 is a perspective view of a ribbon-vibrating mechanism of an "Underwood" front-strike writing-machine, showing the ribbon-vibrator operatively connected to the actuator, so that the ribbon is thrown up to cover the printing-point at each type impression, the parts being shown in normal position. Fig. 2 is a similar view showing the ribbon-vibrator silenced by reason of a disconnection thereof from the reciprocatory actuator, a type-bar being shown in printing position and printing off the ribbon.

Types 1 upon the front ends of type-bars 2 strike against the front side of the platen 3, said type-bars being pivoted at 4 and having heels 5 to press rearwardly a curved universal bar 6, the latter fixed upon a reciprocating frame 7. Erected upon said frame is an actuator 8, having a vertical slot 9 to receive

a wrist 10, provided upon a short arm 11 of a lever 12, which is connected at 13 to an up-standing carrier 14, through which is threaded an ink-ribbon 15. Said lever is pivoted upon a bracket 16, secured to a rail 17, upon which travels the frame that carries the platen 3, said rail 17 forming part of a frame 18, which is vibrated up and down to shift the platen for writing capital and small letters. The slot 9 in the actuator is sufficiently high to accommodate this shifting movement.

The wrist 10 is formed upon the end of a horizontal shaft 19, which is mounted in a long bearing or boss 20, formed upon the lever-arm 11, the shaft being slidable through said bearing, so as to withdraw the wrist 10 from the slot 9, Fig. 2, thereby silencing the ribbon-vibrator 14. For convenience in unshipping the wrist 10 I provide upon the opposite end of the shaft 19 a head 21, received in a cross-fork or slotted member 22, provided upon the end of a slide 23, the latter having slots 24 to receive guiding-screws 25 and also having a finger-piece 26 projecting at the side of the machine convenient to the operator. Normally the finger-piece and slide are pressed in, Fig. 1, so as to maintain the wrist 10 in its normal position in the slot 9, the friction of the slide upon the heads of the screws being sufficient to hold the slide 23 wherever it is set. The cross-fork 22 is parallel with the direction of the motion of the actuator 8, so that the movement of the lever is not interfered with, the head 21 moving idly backward and forward in said fork or slotted member. When it is desired to write off from the ribbon, the finger-piece 26 is drawn out, Fig. 2, unshipping the wrist 10 from the slot 9, so that the lever 12 and vibrator 14 are silenced.

Having thus described my invention, I claim—

1. In a type-writing machine, the combination of an actuator having a slot, a ribbon-carrier, a lever therefor, a wrist engaging said slot and slidable in said lever and having a head, a slide having a cross-slot engaging said head, and a finger-piece upon said slide, the latter movable to disconnect said wrist from said actuator, to silence said vibrator at will; said wrist formed upon a shaft having a long bearing in said lever.

2. In a type-writing machine, the combination of a ribbon-carrier, a lever for operating the same, a platen-shifting frame whereon said lever is pivoted, a shaft movable endwise in a long bearing provided in said lever, a wrist upon one end of said shaft, a head upon the other end of said shaft, a slide having a cross-fork engaging said head and provided with a finger-piece, a frame which re-

ciprocates at the type-strokes, and a vertically-slotted actuator upon said frame, said finger-piece and slide being movable to disengage said wrist from said slotted actuator, to silence said vibrator at will.

HERMAN L. WAGNER.
